UNITED STATES PATENT OFFICE.

ADOLF KRAUSS, OF CANNSTATT, GERMANY, ASSIGNOR TO THE FIRM OF ROBERT BOSCH, OF STUTTGART, GERMANY.

BRUSH-HOLDER.

1,093,634.

Specification of Letters Patent. Patented Apr. 21, 1914.

Application filed May 23, 1911. Serial No. 629,017.

To all whom it may concern:

Be it known that I, ADOLF KRAUSS, a subject of the Emperor of Germany, residing at Cannstatt, Germany, have invented 5 certain new and useful Improvements in Brush-Holders; and I do hereby declare the following to be a full, clear, and exact description of the invention, such as will enable others skilled in the art to which it 10 appertains to make and use the same.

The present invention relates to brush holders for electrical apparatus, and particularly to a brush holder well adapted to use in distributor for electrical ignition 15 systems for multiple cylinder internal combustion engines.

Distributors for this purpose often comprise a cylindrical housing with distributor contacts mounted on the inside thereof and 20 electrically connected to the various spark plugs in the engine cylinders, whereby a rotating brush successively connects the source of electric current to the spark plugs. The brush and the distributor contacts are subject to wear and vibration in operation and 25 to variation in assembling so that it is generally customary to provide a spring for feeding the brush to compensate for such occurrences. However, in former devices 30 of this kind, the outward movement of the brush was not limited so that when the housing was dismantled for inspection or repair, the brush was not retained in place, and upon subsequent re-assembling of the 35 parts considerable difficulty was experienced.

In accordance with this invention, a cap constituting a closure for the distributor housing also carries the distributor contacts. A brush, which during rotation, successively 40 connects the distributor contacts to the source of current supply, is held in a brush holder comprising a guide for the brush, a spring which continually presses the brush outwardly against the distributor contacts 45 to effect good electrical contact therewith under all conditions, and suitable means for limiting the outward movement of the brush. In this way the brush is retained in the holder when the cap is removed for 50 the purpose of inspection or repair of the distributor elements.

In the accompanying drawings illustrating the preferred embodiment of my invention and modifications thereof, Figure 1 is a 55 central section through the distributor; Fig.

2 is an end view of the interrupter, partly in section; Figs. 3, 5 and 7, are side views and Figs. 4, 6 and 8 are end views, partly in section, of modifications of the brush holder.

In Fig. 1, 9 is a cap of insulating material constituting a closure for the housing of the distributor. There may be any number of distributor contacts and they may be of any shape and disposed in any order or 60 relation desired. In the drawings herein shown there are four distributor contacts, 11, 12, 13 and 14, of suitable conducting material mounted in recesses so as to be flush with the inside surface of the cap to form 65 a smooth path for the rotating brush. The binding posts 15, 16, 17 and 18 are separately connected to the distributor contacts and are separately connected by the wires 19, 20, 21 and 22, with respective spark plugs 70 in the cylinders of an internal combustion engine, in accordance with well known principles.

An ignition machine of any type for producing ignition currents is represented in 75 part by 23, while a portion of the frame thereof indicated by 24 carries a journal box 25 in which the journal bearing 26 rotates. The gear wheel 27 is operatively connected 80 with the engine in any suitable manner (not 85 shown) and is fastened on the journal bearing 26.

The brush holder consists of a radial block 90 of insulating material K securely mounted upon a spindle k which tightly fits within the journal bearing 26 so as to rotate when 95 the gear 27 is rotated. A cup-shaped sleeve H of conducting material affords a radial guide for a brush C of carbon or other suitable material which is pressed outwardly by a helical spring e. The inner end of the guide H is electrically connected with the metal cap h at the outer end of the spindle k by an insulated conductor l, as shown in 100 Figs. 1 and 2, so that the current produced by the ignition machine passing to the cap h by means of a sliding contact, is then conducted to the brush C by the conductor l and the guide H, and thence to the distributor contacts in succession as the brush is rotated.

Although it is not essential, I prefer to construct the guide H so that it projects beyond the outer end of the block K and near to the distributor contacts, in order that the 110

brush will be securely held in the guide even after considerable wear. A hook-shaped member F of resilient material is fastened to the guide with its hooked end projecting 5 within an elongated channel f in the brush, whereby the outward movement of the brush is limited by the engagement of the hook with a stop formed by the inner end of the channel f in the brush. It is obvious that 10 the member F may be fastened to any other part of the rotating element such as the insulating block K. The co-acting hook-shaped member and the channel in the brush are so designed that the outward movement 15 of the brush is sufficient to permit good electrical contact with the distributor contacts even after considerable wear of the brush or in cases of considerable variation in assembling. However, when the cap 9 is 20 removed for inspection or repair of the distributor elements, the outward movement of the brush is limited so that the brush C is retained in the guide when its outward movement is not otherwise restrained. If 25 desired, I may provide two or more of such hooks and channels, but in any case the re-assembling of the parts is facilitated. When it is necessary to remove the brush for any purpose, the resilient hook-shaped 30 member F may be pulled out of engagement with the channel in the brush by hand, while a brush may be inserted in the holder by a similar operation.

Figs. 3 and 4 show a modified arrangement comprising the brush C formed with an abutment f adapted to engage a hook F at the extreme outward position of the brush. Figs. 5 and 6 show other means for limiting the outward movement of the brush 40 comprising a pin s extending rigidly through the brush C and projecting within elongated slots S in the guide H. In Figs. 7 and 8 the construction for limiting the outward movement of the brush is similar to that of Figs. 5 and 6 except that the pin s is fixed in the guide H and passes through an elongated slot S in the brush.

It is obvious that the construction herein shown may be modified in many particulars 50 without departing from the essential features of my invention. The elements composing the ignition system may be constructed and arranged in various ways; the brush may be fixed in position while the

distributer contacts rotate; the means for 55 rotating the brush may be variously modified in any well known manner; the method of connecting the brush in the ignition circuit may be variously changed; and also several such brushes may be arranged on the 60 same spindle for other purposes which are well known.

The characteristic feature embodied in the invention is that a brush adapted to successively engage a plurality of distributor 65 contacts is retained in a brush holder of such construction that the brush is pressed outwardly against the distributer contacts but has its outward movement limited so that it is retained in the holder when its outward 70 movement is not otherwise restrained.

Having thus described my invention, what I claim is:

1. In electrical apparatus, a brush having a channel therein, a brush holder having a 75 guide for the brush, a spring adapted to feed the brush outwardly of the guide to compensate for wear, and a hook-shaped member engaging said channel and cooperative with the end thereof to limit the outward 80 movement of the brush; substantially as described.

2. In electrical apparatus, a rotatable brush holder having a radial guide, a brush mounted in said guide and having a channel, 85 a spring adapted to feed the brush radially outward to compensate for wear, and a resilient hook-shaped member engaging said channel and cooperative with the end thereof to limit the outward movement of the brush; 90 substantially as described.

3. In electrical apparatus, a brush holder of insulating material having a radial guide projecting within the block and outside the end thereof, a brush mounted in said guide 95 and having a stop, a spring adapted to feed the brush radially outward to compensate for wear, and a resilient hook-shaped member adapted to engage a stop on the brush to limit its outward movement; substantially 100 as described.

In testimony whereof I affix my signature, in presence of two witnesses.

ADOLF KRAUSS.
